UNITED STATES PATENT OFFICE

ROBERT E. COLLINS, OF TOPEKA, KANSAS, ASSIGNOR OF ONE-FOURTH TO CONSTANTINE
G. CHUMOS, OF TOPEKA, KANSAS

COIN-OPERATED LIQUID-DISPENSING MACHINE

Application filed June 9, 1928. Serial No. 284,037.

The present invention relates to improvements in coin operated automatic liquid dispensing machines, and has for an object to provide a gasoline or other liquid vending machine of the general type shown and described in my co-pending application, Serial No. 254,098, filed February 13, 1928, in which the device is operably associated with a coin controlled mechanism so arranged and connected that the vending mechanism may deliver a predetermined quantity of the liquid only after the insertion of a proper coin in the coin controlled mechanism.

Another object of the present invention is to provide a liquid dispensing device in which the use of an attendant is entirely dispensed with, and whereby the liquid may be dispensed automatically by the machine, for instance at night after the gasoline station is closed.

A further object of the invention resides in providing an improved liquid dispensing machine in which the action is under the control of a coin governed mechanism having as a part thereof a device to automatically make change.

A still further object of the invention is to provide, in connection with a liquid dispensing or other machine, a coin controlled mechanism and associated change making device, in which the change making device is subject to adjustment for repeatedly delivering a fixed sum in change upon deposit of a coin of predetermined denomination.

Other objects of the invention are to provide a coin controlled device which can only be operated subsequent to the insertion of a coin within the device, and only by means of the coin; to provide means whereby a predetermined amount of change or coins of small value will be delivered to the operator only after an initial coin of predetermined denomination has been properly inserted in the machine and only after the machine has been operated to cause delivery of the quantity of liquid for which it is set; to provide a liquid dispensing machine and a coin controlled mechanism, individually and collectively of simple and compact construction associated

in a novel and compact manner for simple and ready operation.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 shows a side elevation, with parts broken away and parts illustrated in section, of a gasoline or liquid measuring and distributing machine, and a coin operated controlling mechanism therefor.

Figure 2 is a top plan view of the coin operated controlling mechanism for said machine with certain parts shown in section.

Figure 3 is a vertical sectional view of the controlling mechanism taken on the line 3—3 of Figure 1 and looking in the direction of the arrows.

Figure 4 is an enlarged detail side view, with parts broken away and parts shown in section, of the change making mechanism or coin delivering apparatus, and

Figure 5 is an enlarged sectional detail showing the electrical contacts employed for closing a circuit by means of the coin.

Referring more particularly to the drawing, 10 indicates the ground line or surface of a gasoline filling station conventional for automobiles. Numeral 11 indicates upright supports or legs, and 12 a housing which is adapted to surround the mechanism and prevent unauthorized persons from tampering with the interior arrangement of its parts; it being understood that the fragment of the housing 12 which is shown is continued upon all sides of the machine.

Numeral 13 indicates a cylindrical container or measuring device mounted upon the support or legs 11, said container preferably being formed of transparent glass. 14 and 15 respectively indicate the bottom and top of the member 13 and 16 indicates a vent hole cap. The numbers 14 and 15 are preferably formed of metal. 17 indicates a graduated scale formed upon the side wall of the mem-

ber 13, its graduations denoting gallons of gasoline.

Numeral 18 indicates a storage tank for containing compressed air, which is supplied by a compressor engine run by a motor, the latter two elements not being shown. 19 indicates a conduit pipe adapted to conduct the air from the compressor engine to the tank 18, the latter being preferably placed above the ground. 20 indicates a pipe leading from the pressure tank 18 upwardly for purposes later described. The pipe 20 is provided with a pressure reducing valve 21 shown in dotted lines, which is adapted to reduce the pressure of the storage tank to a pressure, of say, thirty pounds to the square inch.

Numeral 22 indicates a pipe leading from the mechanism above the ground to a small auxiliary tank 23, which is placed below the ground. The upper ends of the pipes 20 and 22 are adapted to have communication with each other by opening a valve 24.

A pipe 25 is connected with the bottom of the auxiliary tank 23 and is connected to the bottom of the measuring device 13, and is provided with a check valve 26. A pipe 27 is attached to the bottom of the measuring device and is in communication with an outlet pipe 28 at desired times and at other times said communication is cut off by means of a valve 29. The pipe 28 is in communication with a flexible hose 30 which is provided with a nozzle 31.

The measuring device 13 is in communication at all times with an over-flow pipe 32. The pipe 32 extends downwardly and is in communication with a gasoline or liquid storage tank 33 which is preferably located below the ground and is of large capacity.

Within the over-flow pipe 32 a bucket 34 is placed. The bucket is provided with a plurality of small apertures 35 which extend through its bottom portion in a manner whereby liquid contents placed within the bucket will gradually seep through or leak through said apertures. The bucket is suspended upon a wire 36 which extends through the overflow pipe 32. The valve 29 is provided for cutting off the flow of liquid from the member 13 to the hose 30.

About the overflow pipe 32 is placed a housing 39 which is attached to the bottom 14 of the measuring device 13. The housing 39 encircles the overflow pipe 32 in a manner whereby leakage of gasoline from the member 13 will be prevented. The interior diameter of the housing 39 is larger than the exterior diameter of the overflow pipe 32 and in the space thus formed a tubular adjustable member 40 is loosely positioned whereby it is adapted to have vertical reciprocating movement. A rod 41 is attached to the bottom of the tubular member 40 and extends outwardly of the housing 39 and downwardly, leakage at this point being prevented by means of a

packing ring 42. Upon the lower end of the rod 41 and exteriorly of the sides of the housing 12, a handle 43 is provided. An adjustable indicating finger 44 is mounted upon the rod 41. At any convenient point, such as upon the side wall of the device or a leg thereof, an indicating scale 45 is provided. The graduations of the scale 45 correspond with the graduations of the scale 17 formed upon the measuring vessel 13. Adjacent the scale 45 lugs are provided as shown at 46 whereby upon the placement of the indicating finger 44 upon said lugs, the adjustable tubular overflow pipe 40 will be held and prevented from downward movements. A housing 47 for the valves 24 and 29 is provided. The housing is provided with a chamber 48 which is in communication at all times with the pipe 20 and a second chamber 49 is likewise in communication with the pipe 22.

The valve 24 is attached to its stem 50 by any suitable means and it will be understood that when the stem 50 is moved outwardly that communication will be established between the pipes 20 and 22. A vent 51 is provided upon the valve housing 47 whereby communication with the atmosphere is at all times established with an interior chamber 52 of the valve. Communication between the chambers 49 and 52 may be prevented at desired times by means of a valve 53 which is slidably and loosely mounted upon its valve stem 50. It will be noted that upon a movement of the valve stem 50 that the valve 53 will seat and cut off communication between the chambers 49 and 52 since the valve 53 is provided with a spring 54 which when the stem 50 is moved upwardly, is of greater resistance than thirty pounds, air pressure. The spring 54 is provided with a pin or keeper 55, said pin being mounted through the stem 50.

The valve 29 is adjustably mounted upon its stem 50 by means of a threaded nut 56. A semi-circular shaped button 58 is provided upon the end of the valve stem 50 outside of the casing 47. Within the casing is a coil or other spring 59 abutting against a fixed part within the casing at one end and against the valve 29 at the other end, or being otherwise so disposed as to return the valve stem 50 toward the right, or to the position indicated in Figure 1, which is its normal position.

A flat or other spring 37 is carried by the end portion of a reciprocating rod 71 and bears against a lever 60 for the purpose of normally holding up the receptacle 34, which is connected to the lever 60 through the wire 36. The lever 60 is pivoted, as indicated at 61, upon the end portion of the reciprocating actuating shaft or rod 71; and said lever is provided with an upstanding lug 62 in the path of the head 58, said lug having a beveled face at one side and an abrupt right angular face at the other side.

At 70 is shown a housing for the coin controlled mechanism, which may be attached in any suitable manner and by any suitable means to the liquid dispensing machine. The shifting or reciprocating rod 71 is positioned to slide through the housing 70 and it is provided with a handle 57 exteriorly for manipulation by the customer or purchaser.

A notch 73 is made in the shaft 71 to receive a locking dog 74, pivoted at 75 to the casing, as shown in Figure 3. The latch or dog 74 will descend by gravity into locking engagement with the shaft 71 and prevent its operation. The dog 74 constitutes an armature or is connected to the armature, for an electromagnet 76, positioned above, or adjacent, the dog and supported within the housing 70 in any appropriate manner. This electromagnet is arranged to be energized by a battery or other source of current indicated at 78 through the circuit wire 77, by which the battery communicates directly with the electromagnet, and the wires 79 and 81 which connect the other side of the battery with the opposite side of the electromagnet through the coin 84, when such coin reposes in the coin chute 83. This construction is more particularly shown in Figure 5, in which 80 and 82 represent binding posts connected respectively to the electrical contact plates 86 and 85 which are electrically connected with the binding posts and therefore with the circuit wires, but which are insulated from the surrounding walls of the coin chute.

The plate 86 may be curved at its lower or inner end to interpose an obstacle to the free passage of the coin and to retain the coin in position across the plates 85 and 86 until such time as the coin is forcibly dislodged. The plate 86 is also preferably pivoted and associated with a spring 87 which holds the plate in the position, shown in Figure 5, until the applied force referred to is exercised to rotate this plate and dislodge the coin, whereupon it will fall into the bottom of the casing 70 or into a suitable coin depository place therein. Any suitable means may be provided for ejecting the coin 84 from between the resilient contacts 85 and 86, the means shown in the instant case consisting of a finger 88, which is pivotally attached to the shaft 71, as shown at 89. As illustrated in Figure 1, the finger 88 is in a normal position, which position it occupies before the shaft 71 is moved; and it will be understood that, when the operator moves the shaft 71 outwardly, the sharp lower point of the finger 88 will be moved to the opposite side of the coin 84 and that, when the shaft 71 returns to a normal position, influenced by the spring 72, the finger 88 will pry or move the coin 84 outwardly from between the contacts 85 and 86, it being understood that the coin 84 makes a close fit within the slot, and that the upper edge of the contact 85, as shown in Figure 2, is slotted

in a manner to permit the sharp lower edge of the finger 88 to come in contact with the coin 84.

Upon the shaft 71, an outwardly projecting arm 90 is provided, so disposed as to strike one arm of a bell crank lever 91 pivotally mounted upon a shaft 92 supported within the housing 70. The other arm of the bell crank lever is attached to a rod 93. The upper end of the rod 93 is coupled to an arm 94 rigid upon a shaft 95 pivotally journaled within the housing by any suitable means, such as shown at 96. A plurality of arms 98 are adjustably secured to the shaft 95, as by the set screws 99, whereby the arms may be shifted angularly about the shaft, as for instance shown in the full and dotted line position in Figure 4.

These arms 98 are arranged to operate the change making mechanism, which is of a conventional form in use today by street-car conductors and the like. It consists primarily of one or more tubular members 100 for containing stacks of coins 101. These tubular members are supported from the side walls of the housing by shelves 102. The last coin upon the bottom of each stack is adapted to be moved outwardly by the following mechanism, which is the same for each change making device.

The push member 103 slides along the shelf 102 and is adapted to move out the lowermost coin from the stack. The member 103 is hinged, as at 104, to a connecting link 105. The latter in turn is pivotally connected at 106 to a swinging arm 107, which extends upwardly and is pivoted at 108 to a wall of the casing or other part. A spring 109, which is preferably rectangular in cross section is arranged to bear upon the arm 107 for the purpose of returning the slide 103 and connected parts to a normal position which is toward the wall 70 in Figure 4. The member 103 is shifted outwardly to dispense a coin from the holder 110, as follows:

A lever 110 is pivotally mounted, as at 111 to a fixed part or casing wall and bears against the arm 107 at the point *x* (Figure 4) at the side opposite that engaged by the spring 109. The lever 110 is adapted to loosely encircle the coin container 100 and is provided with an outwardly extending portion 112 situated in the path of the respective tappet or finger member 98. One such tappet or finger member 98 is provided for the lever of each change making mechanism. The dispensed change 101 drops from the shelf on to a chute 114 by which it is deflected to a cup or receptacle 113 upon the exterior of the casing 70. When the operator moves the shaft 71 outwardly, the motion is communicated through the bell crank lever 91, rod 93 and arm 94 to the shaft 95; and since the members 98 are secured to the shaft 95 by means of the set screws 99, the motion

of the shaft or actuating rod 71 will be communicated to the members 112.

A downward movement of one or all of the members 98 will cause a corresponding downward movement of the lever 112 for ejecting a coin from the holder 100. These holders 100 may be in any suitable number such as for holding stacks of pennies, nickles, dimes and quarters.

10 The operation is as follows:—

Assuming that the dispensing mechanism has been set and locked by the filling station attendant so that it will dispense no more and no less than five gallons of gasoline during one operation, as heretofore described in my co-pending application above referred to; and further assuming that the current price or value of five gallons of gasoline is ninety-five cents; and assuming that a customer drops a silver dollar in the coin chute 83, then this silver dollar represented at 84, completes a circuit through the electromagnet 76, energizing the magnet and causing it to attract its armature or locking dog 74 out of locking engagement with the slot 73 of the actuating rod or shaft 71 enabling such rod or shaft to be pulled outwardly by the customer engaging the handle 57. The difference between the value of the deposited coin, namely one dollar, and the value of the gasoline being five cents, the machine will automatically make change for this amount and deliver such change to the exterior of the machine, or in other words to the external receptacle 113 where it may be picked out by the customer.

40 The operation of the tappet 98 for the various change making units from the movement of the rod or shaft 71 has already been described. These dogs, arms or tappets 98 may be all set in the raised position indicated in dotted lines in Figure 4, with the exception of that particular dog 98 which registers with the five cent stacks of coins. In this manner, a downward movement of the rod 93 will cause one coin, denomination five cents, to be ejected for each pull of the shaft or rod 71 and no coins from the one cent, ten cent or twenty-five cent stack of coins will be dispensed, since the dogs 98 for the latter are in the raised position, such dogs having been raised and set-screwed in this position by the gasoline station attendant when he set the machine for the night.

55 It is obvious that the machine may be set by the operator, so that it will dispense any selected coin, or any selected number of coins for each pull of the shaft 71 in accordance with the retail price of gasoline.

60 It will be understood that coin testing devices not shown, may be utilized with the device, if preferred, and that the coin chute or slot 83 may be curved or shaped in a manner whereby an unauthorized person would be prevented from inserting a piece of

metal other than a coin into the slot for closing the circuit.

It is also obvious that the device may be arranged so that the coins 84 introduced into the coin chute are exposed to view, if desired. In the latter case the device is useful during the day time while a filling station attendant is adjacent the machine for detecting spurious coins and to save the attendant's time in making change. It is also obvious that, by use of a coin testing device, the present mechanism is useful for automatically selling gasoline during the night time when the filling station attendant is not about the filling station.

70 When the device is employed to sell gasoline at night, the operator adjusts the rod 41 and over-flow pipe 40 and locks it in the adjusted position for the night, so that a predetermined quantity, for instance five gallons, of gasoline can be dispensed by the machine for each pull upon the operating rod 71.

75 When the shaft 71 is pulled out, the lever 61 is moved so that the lug 62 strikes the head 58 and shifts the valve stem 50 to the left opening the valve 24 and closing the valves 53 and 29. Thereupon, compressed air from the receptacle 18 passing through pipes 20 and 22 will lift the gasoline through the pipe 25 to the measuring receptacle 13 as stated in my previously mentioned co-pending application. This gasoline will rise in the measuring receptacle 13 until it reaches a volume of five gallons whereupon it will begin to 100 overflow the pipe 40.

80 This overflow will be partially caught in the receptacle 34 and when sufficient weight of gasoline accumulates in the receptacle 34 to out-weigh the load of the spring 37, the lever 60 will be pulled down withdrawing the dog 62 from engagement with the head 58. The coil spring 59 will then return the valve stem and valves to the normal position shown in Figure 1. The measured quantity of gasoline in the measuring device 13 will then flow out the hose into the vehicle tank.

85 I do not wish to be restricted to the size, form, and proportions of the various parts, and obviously changes could be made in the construction herein described without departing from the spirit of the invention, it being only necessary that such changes fall within the scope of the appended claims:—

90 What is claimed is:—

1. In a change-making device, an operating member, a pin on the operating member, a bell-crank lever positioned to be moved by said pin, a rock-shaft, an arm on the rock-shaft, a link connecting said lever and shaft, magazines for coins, and means operable from said rock-shaft for ejecting coins from said magazines.

120 2. In a change-making device, coin magazines, slides to eject coin from the maga-

zines, pivoted arms connected to said slides, spring means acting on the arms to hold the slides in an initial position, levers engaging said arms, tappets for striking said levers and operating means for said tappets.

5 3. In a change-making device, coin magazines, a shelf spaced below the magazines, slides movable along the shelf beneath the magazines, pivoted arms coupled to said slides, spring means acting on the arms to hold the slides in an initial position, slotted levers extending about said arms and spring means and bearing against the arms to move same together with the connected slides, and
10 15 selectively-adjustable tappets for striking said levers.

4. In a change-making device a casing, a shelf therein, coin magazines above the shelf, slides movable along the shelf beneath the magazines, links coupled to the slides, arms pivoted to the links and to the casing, springs fixed in the casing and bearing against the forward edges of the arms, slotted levers fulcrumed in the casing and bearing against the rear edges of the arms, said levers extending about the arms and springs, and selectively-adjustable tappets for actuating said levers.

In testimony whereof, I have affixed my
30 signature.

ROBERT E. COLLINS.
